Patented Oct. 3, 1967

208,788

TOY STEERING WHEEL

Raymond J. Lohr, Erie, Pa., assignor to Louis Marx & Co., Inc., New York, N.Y., a corporation of New York

Filed Jan. 26, 1966, Ser. No. 775

Term of patent 14 years

(Cl. D34—15)

FIG. 1

FIG. 2

FIG. 3

FIG. 4

FIG. 1 is a bottom perspective view of a toy steering wheel embodying my new design;

FIG. 2 is a bottom plan view thereof;

FIG. 3 is a top plan view thereof; and

FIG. 4 is a side view thereof.

The broken line showing of a steering shaft in FIGS. 1 and 4 is for illustrative purposes only.

I claim:

The ornamental design for a toy steering wheel, as shown and described.
